UNITED STATES PATENT OFFICE.

NATHAN BRILES, OF CUSTER, OKLAHOMA.

AUTOMATIC TEMPERATURE-CONTROLLED RECEPTACLE.

1,142,075.

Specification of Letters Patent.

Patented June 8, 1915.

Application filed August 13, 1914. Serial No. 856,570.

To all whom it may concern:

Be it known that I, NATHAN BRILES, a citizen of the United States, residing at Custer city, in the county of Custer and State of Oklahoma, have invented certain new and useful Improvements in Automatic Temperature-Controlled Receptacles; and I do hereby declare the following to be a full, clear, and exact description of the invention, such as will enable others skilled in the art to which it appertains to make and use the same.

This invention relates to receptacles and in particular to semen holding receptacles.

One of the objects of this invention is to give an automatic device whereby the semen retained within the receptacle is kept at constant blood heat.

Another object of this invention is to give a device whereby if the receptacle becomes too hot it will automatically cool till it reaches a point of blood heat.

Still another object of this invention is to give a device whereby the semen containing jars held within the special receptacle are surrounded by a water jacket in which the temperature of the water jacket is maintained at a constant degree of temperature.

A still further object of this invention is to retain a thermometer within said receptacle and perceptible outside of said receptacle to indicate the internal temperature of said receptacle.

Still another object of this invention is to give a device whereby the flame of the lamp which heats the water jacket surrounding the semen containing jars can be perceived externally of the receptacle.

A still further object of this invention is to give a device whereby a plurality of semen holding jars retained within the special holding receptacle are heated at a uniform temperature and maintained at such uniform temperature from one source.

Other objects and advantages of this invention will be hereinafter more clearly set forth in the specifications and pointed out in the claims.

Similar characters of reference refer to similar parts throughout the drawings in which,

Figure 1, is a sectional elevational view of this device in assembled formation, and Fig. 2, is a sectional elevational edge view of this device in assembled formation looking at right angles to that shown in Fig. 1.

In the drawings, 1 is a casing comprising my special receptacle, said casing having a handle 2 thereto, and a lid 3 thereto, said lid being of special formation to be hereinafter described in detail. A circumferential corrugation 4 projects internally within said receptacle near the lower portion thereof, the purpose of which will be hereinafter described. A window 5 is in said receptacle and a door 6, said window and said door being hereinafter more fully described. Said receptacle has a bottom 7, and a special formed water jacket 8 of the contour of the inner wall of said receptacle, is placed within said receptacle until the bottom 9 thereof comes in contact with the circumferential corrugation 4, said corrugation acting as a support for said water jacket 8, in such manner as to retain the bottom 9 thereof in spaced relationship from the bottom 7 of the receptacle 1. This water jacket comprises a water retaining space 10, and has formed therein a plurality of apertures or jar recesses 11, said recesses adapted to snugly seat the jars 12, holding the semen derived from a jack and stallion respectively. Centrally disposed within said water jacket and integral therewith is a flue 13, said flue opening from the top of said receptacle through to the bottom chamber 14 thereof, and communicating with said chamber 14 formed between the bottom 7 and the bottom 9 of the receptacle and water jacket respectively. The upper end of this flue 13 projects slightly beyond the top of the receptacle. A filling vent 15 is formed in the water jacket, said filling vent being closed by the knurled cap 16, said filling opening adapted to allow said water jacket to be filled and emptied of water. Each of the jars 12 has a removable cover 17 and the receptacle 1 has a lid 3 of special formation, said lid having a centrally disposed opening with upturned flanges 18 thereto adapted to seat over the walls of the flue 13, and a circumferential flange 19 adapted to seat upon the upper edges of the receptacle 1. A plurality of truncated or concaved depressions 20 are formed in said lid 3, said depressions 20 having an aperture 21 at the lowest point therein, said apertures seating directly over the mouths of the jars 12. Said depressions are adapted to receive the semen and fill the same into the jars after the covers 17 have been removed, said covers 17 being replaced after the semen is delivered to the jars.

A lamp 22 having the usual burner and wick formation 23 is placed within the chamber 14 directly under the flue 13 and has a flame and smoke directing chimney 24 seated in the customary brackets 25 therearound, said chimney contacting with the lower corner of the water jacket 8. A thimble or sleeve 26 is suspended around the wick 23 of the lamp, said thimble or sleeve 10 being suspended by means of a rod 27. This rod is threaded as at 28 at the end thereof, and is adapted to adjustably seat a threaded nut 29, said threaded nut supporting the rod 27 upon the arm of a bell crank lever 30, a suitable aperture being had in the bell crank lever for this purpose. This bell crank lever is pivoted from a suitable bracket 31 attached to the flanges 18 previously described, and an opposite arm 20 of the bell crank lever 31 is apertured and seats a link rod 32, said link rod holding a threaded nut 33 thereupon to give suitable adjustment to the link rod 32. The opposite end of the link rod 32 is pivoted in a lever 34, said lever being pivoted as at 35 to the top of the lid 3. The opposite end of the lever 35 is in contact with a thermostat 36 of any desired form of construction. A special receptacle 37 is formed within the 30 water jacket and is adapted to retain a thermometer 38, said thermometer being perceived through a slot 39 within the walls of the water jacket, and a window 40 within the walls of the casing 1. The door 6 35 through which the lamp is placed in position likewise has a peep hole 41 covered by a glass 42 so that the flame of the lamp can be perceived from the outside.

In operation the water is placed within 40 the water jacket 8, the covers 17 are removed from the jars 12, the semen received from the jack is dropped in one receptacle, being fed through the aperture 21 in the depression 20 of the lid 3 previously described, and 45 the semen of the stallion is dropped in a jar 12 through the opening 21 in like manner, said covers 17 are replaced, the lamp is positioned into place and lighted and the thermostat adjusted to actuate at 98 degrees 50 or blood heat in such manner as to retain this measurement of heat within the receptacle. If the heat becomes too intense and above 98 degrees or blood heat, the thermostat expands which throws the upper 55 end of the lever 34 out and raises the bell crank lever through the link 32 so that the lever or thimble 26 is raised around the wick 23 so that the device is cooled. As the device cools the thermostat contracts and allows 60 the thimble to drop through the medium of the structure previously shown and described. This device can likewise be man-

ually raised if the same refuses to act, provided the thermometer 38 previously described is shown as registering an excessive 65 degree of heat which same can be perceived through the window and slot 39 and 40 previously noted. And again the flame of the lamp can be raised or lowered as the same is perceived to be needed when looked 70 at through the peep hole 41 and the glass 42 covering the same.

Having described my invention what I claim as new and desire to secure by Letters Patent is,

1. A device of the character specified comprising a casing, a cover therefor, a water jacket supported in said casing above the bottom thereof and provided with a central opening or flue, a lamp located in the casing below said flue, a thermostatic controller for the flame of the lamp, said controller comprising a thimble surrounding the wick, a hanger rod for said thimble passing up through the flue and the cover of the casing, 80 and a thermostat connected up with the rod above the casing cover.

2. A device of the character specified comprising a casing, a cover therefor, a water jacket supported in said casing above the 90 bottom thereof and provided with a central opening or flue, a lamp located in the casing below said flue, a thermostatic controller for the flame of the lamp, said controller comprising a thimble surrounding the wick, a 95 hanger rod for said thimble passing up through the flue and the cover of the casing, a thermostat within the casing, and connections passing through the cover of the casing from the thermostat to the hanger rod. 100

3. A device of the character specified comprising a casing, a cover therefor, a water jacket supported in said casing above the bottom thereof and provided with a central opening or flue, a lamp located in the casing 105 below said flue, a thermostatic controller for the flame of the lamp, said controller comprising a thimble surrounding the wick, a hanger rod for said thimble passing up through the flue and the cover of the casing, 110 a thermostat within the casing, a lever pivoted in the cover of the casing connected at its inner end to the thermostat, an elbow lever pivoted to the flue with one arm connected to the hanger rod, and a link connecting the outer end of the thermostat lever with the other arm of the elbow lever. 115

In testimony whereof I have signed my name to this specification in the presence of two subscribing witnesses.

NATHAN BRILES.
